UNITED STATES PATENT OFFICE.

THOMAS COSSAR, OF GOVAN, SCOTLAND.

AUTOMATIC REGISTER-GEAR FOR PRINTING-MACHINES.

SPECIFICATION forming part of Letters Patent No. 783,777, dated February 28, 1905.

Application filed March 3, 1904. Serial No. 196,345.

To all whom it may concern:

Be it known that I, THOMAS COSSAR, a subject of the King of the United Kingdom of Great Britain and Ireland, residing at Govan, county of Lanark, Scotland, have invented a certain new and useful Automatic Register-Gear for Printing-Machines, of which the following is a specification.

This invention relates to web-printing machines, especially of the flat-bed oscillating-cylinder type, and has for its object to provide in conjunction therewith improved register-gear for automatically maintaining in register the printing on one side of a web with that on the other side or one or more webs in register with each other. For that purpose the web of paper in passing through the printing-machine to be printed on one side has an orifice punched or perforated in its margin in any well-known way between each of the printings, and in printing the second side the perforations during the travel of the web come in succession under a main tube through which air under pressure is forced. The web or its margin passes over a rotating drum provided with small air-ports and plungers, and according as the rate of feed is above or below the normal, caused by the paper having stretched or shrunk since the first printing or other reason, the compressed air from the main tube escaping through each orifice in the web as it travels over the drum enters into one of the air-ports in front or at rear of a central point to actuate a correspondingly-located plunger, which in the rotation of the drum brings into action either of two pawls to feed forward or backward a wheel acting through a shaft and a train of wheels on register-gear arranged to accelerate or retard the movement of the feed-rollers of the printing-machine.

The invention is illustrated in the accompanying drawings, in which—

Figure 1 is a side elevation of the improved automatic register-gear, and Fig. 2 is a plan of part of the same.

As shown by the drawings, the apparatus comprises a rotating drum A, whose shaft is journaled in the framing B of the printing-machine and has on its end a crank B', connected by a pitman B² with a plunger, thereby

reciprocated with a stationary cylinder C to compress air therein. From the cylinder end a pipe connection leads to a telescopic or adjustable air-tube D, placed over the drum A and having in its lower end an air-outlet directly under which the perforations in the paper web W pass as said web in its travel through the printing-machine passes over the drum, in contact with which it is maintained by rollers E, carried by adjustable levers E' on each side.

In the drum A are a series of small air tubes, ports, or passages a a', having open ends in the periphery of the drum exactly under or in line with the air-outlet of the tube D, these air-ports being preferably of an elongated shape across the drum to provide against side-wise movement of the web, a number of the open ends of these ports a' being at rear of a central imperforate point in the drum's periphery. Each of the ports a terminates in a cylinder a², and each of the ports a' connects in like manner to a cylinder a³, these cylinders a² a³ being arranged in segmental lines on opposite sides of the axis of the drum A and being each fitted with a plunger a⁴ or a⁵, which is normally within the cylinder, but is adapted to be protruded on admission of compressed air to the cylinder and to be returned by the action of a cam-plate N, fixed to the framing B.

Located in proximity to the drum A and to one side of it is a ratchet-wheel F, fast on a shaft F', journaled in the framing B, and on the said shaft as a center is loosely fitted to swing a lever G, oscillated by a pitman G' from the crank B', the said lever G having pivoted near its outer end two pawls g and g', adapted to act in opposite directions on the teeth of the ratchet F, but normally kept out of engagement therewith by means of a segmental hoop F², which has imparted to it a sidewise swing movement by the spring f² on a rock-shaft F³, upon which said hoop is mounted, to cover or uncover the ratchet at proper times, as herein-after explained. Engaging the side hoop F² is a lever H, fixed on a shaft H', journaled in the framing and having secured on its end a bell-crank H² H³, one arm, H², of which is held against a stop H⁴ by means of a spring H⁵, while the other arm, H³, is interposed in the path of the plungers a⁴ a⁵ when these are pro-

truded from their cylinders. When any one of the plungers a^4 is protruded, it strikes the arm H^3 during the forward stroke of the lever G and tilting the lever H raises its free end clear of the hoop F^2 , which swings over to uncover the ratchet-teeth. The forward pawl g then drops into engagement with the ratchet and drives it forward through part of a revolution, while at the end of the stroke a cam-piece G^2 on the lever G engages with a stoppin f on the hoop F^2 and restores it to its position over the ratchet-teeth, while the lever H drops to retain the said hoop in said position.

The pawls g as they reach the end of their travel in either direction are lifted clear of the hoop F^2 by means of lever-arms g^2 g^3 , which come into contact in the cam projections g^4 g^5 at the respective ends of the travel of the pawls, while the outside pawl at the end of each stroke passes over the end of the hoop F^2 to allow the latter to return and shield the ratchet-teeth F . Should none of the plungers a^4 protrude, no action of the lever H occurs during the forward stroke of the lever G and no movement of the ratchet-wheel takes place; but should one of the plungers a^5 protrude from its cylinder it is carried in the rotation of the drum A into contact with the arm H^3 during the backward stroke of the lever G , the ratchet-teeth are uncovered, and the rear pawl g engages them to drive the ratchet-wheel in the rearward direction, while at the end of the stroke the cam-piece G^2 engages a stoppin f' on the hoop F^2 to restore the latter to its normal position, shielding the ratchet-teeth, in which position the pawls g are rendered inoperative.

The cylinders a^2 a^3 and their plungers a^4 a^5 are so placed on the drum that while the plungers of each set farthest from the center imperforate portion of the drum's periphery act on the lever H^3 during the early part of the forward or backward stroke of the lever G the plungers adjoining act at a later period of the stroke, and the last of the plungers—those next to the imperforate part—act toward the end of the stroke, so that a greater or less forward movement is imparted to the ratchet-wheel F and its shaft F' , according as the web is more or less out of its proper position.

The shaft F' has on its end a bevel-wheel J , meshing with a bevel-wheel J' on the end of a shaft K , at whose other end is a worm gear meshing into a worm-wheel L , forming part of the wheel-train of register-gearing which serves to accelerate or retard the feed-rollers M of the printing-machine and which accelerating or retarding gear may be constructed and arranged to operate in a well-known manner, as is exemplified, for instance, in the United States Patent No. 745,572, granted to me December 1, 1903.

In the operation of the apparatus the perforated web passes over the drum A at the

same surface speed as the latter, the drum, which is interchangeable, according to size of work being printed, being in circumference equal to the distance between the perforations in the web. If the feeding of the paper through the printing-machine be regular and uniform, so as to maintain the second printing in register with the first printing, the perforations in the web will in succession pass over a solid portion of the drum's periphery between the two rows of ports a and a' ; but if the web be fed out of register and be faster than the normal rate the perforations in the web, or one of them, will come over one of the ports a , whereupon compressed air will be allowed to pass from the air-tube D into said port and will force out a corresponding plunger a^4 , whereby the ratchet-wheel F and its shaft F' will be operated and transmit movement to the worm-wheel L and train of register-gearing in a direction to retard the rate of feed of the web. If, on the other hand, the web be fed at a slower rate than the normal, the perforations in the web will come over one of the ports a' in the drum A and the corresponding one of the plungers a^5 will be protruded, whereby the action of the ratchet-wheel and transmitting-gear will be in the reverse direction and will act on the registering-gear to accelerate the rate of feed of the web.

The supply of compressed air to the tube D may be obtained from any other available source instead of from a compression-pump operated as described from the drum-shaft.

Having now described my invention, what I claim, and desire to secure by Letters Patent of the United States, is—

1. Register-gear for printing-machines comprising in combination web-feed rollers carrying a perforated web, a plurality of air-ports, means directing compressed air through the perforation of said web into any one of said ports, reciprocating plungers operated by said compressed air passing through said ports, releasing mechanism operated by said plungers and means serving to accelerate and retard said rolls, said means being operated from a suitable source of power and being started and stopped by said releasing mechanism.

2. Register-gear for printing-machines comprising in combination, a rotating drum provided with air-ports, cylinders in which said ports terminate, movable plungers in said cylinders, web-feed rolls carrying a perforated paper web, means for directing air through perforations in said web to said air-ports to protrude a corresponding plunger, lever devices acted on by said plungers, a ratchet or like wheel fed forward or backward, and mechanism for accelerating or retarding said rolls said mechanism being operated by said ratchet-wheel.

3. Register-gear for printing-machines comprising in combination a rotating drum,

a series of plungers actuated by pneumatic power, said power being admitted to said drum by a perforated paper web passing over the same, devices acted on by any one of said 5 plungers, and gearing operated thereby and serving to accelerate and retard the feed-rolls of the printing-machine.

4. Register - gear for printing - machines comprising in combination a rotating drum, 10 plungers or like devices actuated by pneumatic power, said power being admitted to said rotating drum by a printed and perforated web, levers operated by a selected plunger, a ratchet-wheel, a lever provided with 15 pawls which serve to rotate said ratchet during the forward and backward stroke of said pawl-lever, a guard for said ratchet-wheel serving to cover the same and prevent engagement therewith by said pawls said guard being operated by a selected plunger, and power-transmitting gear communicating movement of said ratchet-wheel to said rolls.

5. Register - gear for printing - machines comprising in combination, a rotating drum 25 formed with air-ports over which drum may be led a perforated paper web, cylinders in which said ports terminate, movable plungers in said cylinders, web-feed rolls, means for directing air through the perforations in the 30 paper web to said air-ports to protrude a corresponding plunger, lever devices acted on by the plunger, a ratchet-wheel fed forward or backward thereby, and accelerating and retarding gear for the web-feed rolls, actuated 35 by said ratchet-wheel.

6. Register - gear for printing - machines comprising in combination a rotating drum, a series of plungers actuated pneumatically, 40 rolls for feeding a perforated paper web over said drum, means for directing air through said perforated web, devices acted on by any one of said plungers, and gearing operated thereby to accelerate or retard the feed-rolls of the printing-machine.

45 7. Register - gear for printing - machines comprising in combination a rotating drum over which a perforated paper web may be passed, plungers or like devices actuated pneumatically, web-feed rolls, levers operated by 50 a selected plunger, a ratchet-wheel, a guard therefor connected with said levers and operated by the protruding of a selected plunger, a lever carrying pawls which serve to rotate said ratchet-wheel during the forward or back- 55 ward stroke of said pawl-lever, and power-transmitting gear for communicating corresponding movement to the accelerating and retarding gear.

8. Register - gear for printing - machines, 60 comprising in combination, a rotating drum formed with air-ports, cylinders in which said ports terminate, plungers movable in said cylinders, rolls for feeding a perforated paper web over said drum, gear for accelerating and 65 retarding said feeding-rolls, means for direct-

ing air through perforations in the web to said air-ports, a ratchet-wheel, a swinging lever carrying pawls, means normally covering the ratchet-teeth but uncovering the teeth under the action of said plungers to enable said pawls 70 to engage said teeth and to move said ratchet-wheel, and transmitting-gear communicating corresponding movement to the accelerating and retarding gear.

9. Register - gear for printing - machines 75 comprising in combination a rotating shaft, a drum provided with air-ports said drum being fast on said shaft, a crank on said shaft, a pitman connected to said crank, a cylinder and a piston in said cylinder reciprocated by said 80 pitman, a tube leading from said cylinder and directing a current of air against said drum, cylinders in which said ports terminate, plungers movable in said cylinders, web-feed rolls, lever devices acted on by a selected plunger, a 85 ratchet-wheel fed backward or forward thereby, and accelerating and retarding gear for the web-feed rolls actuated by said ratchet-wheel.

10. Register - gear for printing - machines 90 comprising in combination a rotating drum formed with two sets of air-ports, cylinders on opposite sides of the axis of the drum in which said ports terminate, movable plungers in said cylinders, rolls for feeding a perforated 95 paper web over said drum, a tube for directing air through the perforations in said web into said air-ports to protrude a corresponding plunger, lever devices acted on by said plunger, a ratchet-wheel fed forward or 100 backward thereby, and accelerating and retarding gear for said web-feeding rolls actuated by said ratchet-wheel.

11. Registering-gear for printing-machines 105 comprising in combination a rotating drum located below a traveling perforated paper web said drum having air-ports, cylinders in which said ports terminate, movable plungers in said cylinders, rolls for feeding said perforated web, means for directing air through the perforations in said web to said air-ports to protrude a corresponding plunger, a ratchet-wheel, a lever having pawls, means for oscillating said 110 lever, a guard normally covering said ratchet-wheel, a bell-crank lever in the path of said 115 plungers when protruded, a spring serving to move said guard away from said ratchet-wheel when said bell-crank lever is engaged by a plunger to permit one of said pawls to engage said ratchet-wheel, means for returning said 120 guard to its normal position, and gearing actuated by said ratchet-wheel and serving to accelerate and retard the web-feeding rolls.

In testimony whereof I have signed my name to this specification in the presence of two sub- 125 scribing witnesses.

THOMAS COSSAR.
